[57] CLAIM

The ornamental design for a shoe, substantially as shown and described.

DESCRIPTION

FIG. 1 is a top plan view of a shoe showing our new design.

FIG. 2 is a side elevational view thereof taken in the direction of the arrow 2 of FIG. 1.

FIG. 3 is an opposite side elevational view taken in the direction of arrow 3 of FIG. 1;

FIG. 4 is a front elevational view thereof taken in the direction of arrow 4 of FIG. 1;

FIG. 5 is a rear elevational view thereof taken in the direction of arrow 5 of FIG. 1;

FIG. 6 is a side elevational view of a second embodiment of our new design of FIG. 1, the opposite side being a mirror image thereto;

FIG. 7 is a rear elevational view thereof;

FIG. 8 is a side elevational view of a third embodiment of our new design of FIG. 1, the opposite side being a mirror image thereto;

FIG. 9 is a front elevational view thereof;

FIG. 10 is a rear elevational view thereof;

FIG. 11 is a side elevational view of a fourth embodiment of our new design of FIG. 1, the opposite side being a mirror image thereto;

FIG. 12 is a rear elevational view thereof, the front being identical with FIG. 4;

FIG. 13 is a side elevational view of a fifth embodiment of our new design of FIG. 1, the opposite side being a mirror image thereto;

FIG. 14 is a rear elevational view thereof, the front being identical with FIG. 4.

The bottom views of all embodiments not seen are plain and unornamented.
